UNITED STATES PATENT OFFICE.

OSCAR A. WESTERSON, OF CANNON FALLS, AND WILLIAM A. WESTERSON,
OF MINNEAPOLIS, MINNESOTA.

DRAFT-EQUALIZER.

SPECIFICATION forming part of Letters Patent No. 764,087, dated July 5, 1904.

Application filed February 18, 1904. Serial No. 194,154. (No model.)

To all whom it may concern:

Be it known that we, OSCAR A. WESTERSON, residing at Cannon Falls, in the county of Goodhue, and WILLIAM A. WESTERSON, residing at Minneapolis, in the county of Hennepin, State of Minnesota, citizens of the United States, have invented certain new and useful Improvements in Draft-Equalizers; and we do hereby declare the following to be a full, clear, and exact description of the invention, such as will enable others skilled in the art to which it appertains to make and use the same.

Our invention relates to draft-equalizers, and has for its object to improve the same in the several particulars hereinafter mentioned.

To the above ends the invention consists of the novel devices and combinations of devices hereinafter described, and defined in the claims.

20 The invention is illustrated in the accompanying drawings, wherein like characters indicate like parts throughout the several views.

Figure 1 is a plan view showing our improved draft-equalizer in the form of a four-horse evener applied to a pole, such as the pole of a harvester. Fig. 2 is a transverse vertical section on the line $x^2 x^2$ of Fig. 1, some parts being removed; and Fig. 3 is a section on the line $x^3 x^3$ of Fig. 1, some parts being removed.

30 The numeral 1 indicates the pole. The numeral 2 indicates the primary equalizing-beam, the numeral 3 the two-horse eveners, and the numeral 4 the whiffletrees of the four-horse evener, these elements being connected in the usual or any suitable way.

The number 5 indicates the tugs, shown as connected to the whiffletrees 4 in the usual way.

40 The equalizing-beam 2 is pivoted at its central portion to an oscillating arm 6, which at its inner end is pivoted to the pole by a nutted bolt 7 and is preferably provided with an under side reinforcing-strap 8, which moves pivotally therewith.

The numeral 9 indicates a sheave-supporting bracket which is equipped at its ends with

guide-sheaves 10. This bracket 9 at its intermediate portion is slotted at 11 and is rigidly but adjustably secured on top of the pole 50 back of the oscillating arm 6 by means of a yoke 12. This yoke 12 embraces the pole, and its ends project through the slot 11 of the bracket 9 and are provided with nuts 13, which when tightened firmly clamp the said bracket 55 against the said pole, but when loosened permit endwise adjustments of the said bracket transversely of the pole. Pivotedly mounted on the pole back of the bracket 9 is a third guide-sheave 14. A flexible connection, such 60 as a wire rope or chain 15, extends over the rear portion of the sheave 14 and over the left-hand side of the sheaves 10, and its ends are attached one to each end of the equalizing-beam 2. By adjustments of the bracket 65 9 such an amount of the slack of the connection 15 should be taken up that the arm 6 will stand approximately at a right angle to the pole. Since this arm 6 is prevented from moving forward only by the tension of the 70 rope or connection 15 and as the forward movement of the said connection is resisted by the sheave 14, it is evident that the draft strain will come upon this sheave 14. The connection 15 is, however, free to travel over 75 the said sheave 14 and over the sheaves 10, so as to permit free vibratory movements of the equalizing-beam 2. When the said connection 15 is subjected to draft strains, it exerts 80 a lateral pressure on the sheaves 10 and 85 bracket 9, tending to force the pole toward the right and neutralize the tendency of the pole to be moved toward the left, which latter tendency is due to the fact that the equalizing-beam 2 is pivoted at a point offset from the 85 said pole.

While a four-horse draft-equalizer is illustrated in the accompanying drawings, it will of course be understood that the principles of construction above described may be applied 90 to draft-equalizers in which either a greater or less number of horses are to be attached, such as three-horse equalizers or six-horse equalizers. It will also be understood that

the device described is capable of other modifications within the scope of our invention as herein set forth and claimed.

What we claim, and desire to secure by Letters Patent of the United States, is as follows:

1. The combination with a pole having an offset arm pivoted thereto, of a draft-equalizing device having its equalizing-beam pivoted to said offset arm, a guide-sheave mounted on said pole, at the rear of said arm, a bracket secured to said pole between said arm and said sheave, guide-sheaves mounted on said bracket, one on each side of the said pole, and a flexible draft connection attached at its ends to said equalizing-beam, passed over the rear portion of the guide-sheave on the pole, and passed over two guide-sheaves on said bracket, on the same sides thereof, whereby the side thrust on said bracket is applied in the same direction through both guide-sheaves, substantially as described.

2. The combination with a pole and an offset arm 6 pivoted thereto, of a draft-equalizer, involving an equalizing-beam 2 pivoted to the free end of said arm 6, the bracket 9 rigidly 25 and adjustably secured to said pole, the guide-sheaves 10 mounted on the ends of said bracket, the sheave 14 mounted on said pole at the rear of said bracket, and a flexible draft connection 15, attached at its ends to the ends 30 of said equalizing-beam 2 and passed over the same sides of the said two sheaves 10, and over the rear side of said sheave 14, substantially as and for the purposes set forth.

In testimony whereof we affix our signatures 35 in presence of two witnesses.

OSCAR A. WESTERSON.

WILLIAM A. WESTERSON.
